ROTARY KILN CHAIN ARRANGEMENT

Ray C. Newhouse, Wauwatosa, Wis., assignor to
Allis-Chalmers Manufacturing Company, Milwaukee, Wis., a corporation of Delaware

Application January 22, 1941, Serial No. 375,407

4 Claims. (Cl. 263—32)

This invention relates to chain arrangements for rotary kilns of the type used in burning cement.

For some time it has been common practice to provide cement kilns with heat transferring elements such as chains which aid in the transfer of heat from the gases of combustion within the kiln to the raw material being treated in the kiln. This raw material may be introduced in the form of ground particles or slurry, and is dried, heated to a fusion temperature at which the cement is formed, and discharged from the kiln as a cement clinker to be cooled and crushed. It was found that in some cases the chains impeded the flow of material through the kiln to such an extent as to seriously affect the output capacity of the kiln. To obviate this difficulty a plurality of helical ribs were introduced adjacent the kiln lining in certain zones of the kiln, as more particularly described in U. S. Patent 2,230,601 to B. H. Puerer and E. C. Greisen, dated February 4, 1941.

While the arrangement of combined helical ribs and chains was helpful, it was found that with some materials there was still a zone in the kiln at which the material did not flow smoothly. In fact, at the zone where the material becomes sticky, it would build up until it filled the space between the helical ribs, making the ribs useless at this point.

It is an object of the present invention to overcome the difficulties of prior art kiln chain systems explained above.

Further objects of the invention are to provide auxiliary short slack chains between adjacent ribs in a rotary kiln; to connect such slack chains to the ribs adjacent the lining of the kiln at axially spaced points of the kiln; and to arrange such slack chains so that they sweep over a substantial portion of the surface of the kiln lining during rotation of the kiln.

Further objects will become apparent from the following illustration and the drawing appended hereto wherein:

Fig. 1 is a vertical sectional view of a kiln provided with chains in accordance with this invention;

Fig. 2 is a fragmental development of the interior of the kiln of Fig. 1;

Fig. 3 is a fragmental enlargement illustrating the means for attaching the chains of Figs. 1 and 2;

Fig. 4 is a sectional view taken from the right of Fig. 3;

Fig. 5 is a fragmental sectional view similar

to Fig. 1, but illustrating a modification in which circular ribs are substituted for the helical ribs of Figs. 1 to 4;

Fig. 6 is a transverse section view of the modification of Fig. 5; and

Fig. 7 is a fragmental development view similar to Fig. 2, but illustrating a modification in which the kiln is provided with ribs parallel to the axis of the kiln, rather than the helical ribs of Figs. 1 to 4.

Referring to the drawing in more detail, kiln 10 comprises a metal shell 11 and refractory lining 12, through which pass a plurality of supports 13 which are attached to shell 11 and carry a plurality of helical ribs 14, which are retained adjacent to refractory lining 12. The ribs 14 may be fastened to supports 13 by any suitable bolts 16. So long as the material passing through the kiln flows freely, ribs 14 aid in forwarding the material from the feed end to the discharge end of the kiln.

When the material becomes sticky, however, the channels between adjacent ribs become filled with the material, and the ribs are then ineffective to promote passage of the material. The ordinary long chains used in cement kilns are of little help, since the ribs themselves prevent intimate contact between these chains and most of the kiln lining. To overcome this difficulty, in accordance with this invention, a plurality of short slack chains 17 are mounted adjacent the "bottom" or radially outer portions of the ribs 14, each chain having its ends axially spaced and connected, as at 18, to adjacent ribs.

Chains 17 are made substantially longer than the straight-line or peripheral distance between the attachment points 18 of the ends of each chain, so that each chain hangs with a considerable amount of slack. This results in the slack part of the chain wiping along a substantial part of the surface of the lining during rotation of the kiln in use.

Referring to Fig. 2, for example, it will be noted that as the development section of the kiln shown therein rises during rotation of the kiln, the slack portions of the chain hang down, enclosing a large portion of the lining surface between the points of attachment of each chain and the point of attachment of the next lower chain. These same chains will wipe over the kiln surface and hang in the opposite direction from the points of attachment of each chain during that part of the cycle of rotation when the section of the kiln to which the chain is attached is being lowered. As shown, the areas of surface

lining wiped by each chain preferably overlap the areas wiped by adjacent chains. Due to the slack of each chain and its attachment to adjacent ribs near the surface of the lining, the assembly of chains 17 wipe over most of the surface of the kiln lining, in the zone of the kiln occupied by such chains, and prevents the "plugging-up" of the kiln, as it is commonly referred to in the art.

It is to be understood that the chains of this invention may be used in any desired part of the kiln and will not usually be required throughout the usual chain zone of the kiln. These chains are not intended to be a substitute for the standard chains used in cement kilns, as these will also be required in most cases. The standard chains have not been shown in the drawing in order to avoid confusion.

Figs. 5 and 6 illustrate the chains 27 of the present invention connected at 28 to the radially outer portions of circular ribs 24, which may be utilized in certain kilns. The desired result of sweeping a large portion of the kiln lining surface is obtained by connecting chains 27 with a considerable amount of slack, as shown, to the radially outer portions of adjacent ribs 24.

The chains of the present invention are also applicable to kilns provided with ribs 34 parallel to the axis of the kiln, as shown in Fig. 7. Here chains 37 are connected between adjacent axial ribs 34 at radially outward portions of said ribs, with plentiful slack in each chain. Connection points 38' are shown as being axially spaced from connection point 38, since the two ends of each chain must be axially spaced in order that the slack portion of the chain may sweep over an appreciable area of the surface of the lining between adjacent ribs during rotation of the kiln.

It is claimed and desired to secure by Letters Patent:

1. A rotary kiln comprising a shell, ribs carried by said shell and extending inwardly therefrom, and a plurality of chains within said shell,

each of said chains being located between adjacent ribs and having its ends attached to said adjacent ribs at the radially outer portions of said ribs and at axially spaced points, the length of each chain being substantially greater than the distance along the inner surface of the kiln between the points of attachment of said chain.

2. A rotary kiln comprising a shell, helical ribs carried by said shell and extending inwardly therefrom, and a plurality of chains within said kiln, each of said chains being located between adjacent helical ribs and having its ends attached to said adjacent ribs at axially spaced points at the radially outer portions of said ribs, the length of each chain being substantially greater than the distance along the inside surface of the kiln between the points of attachment of said chain.

3. A rotary kiln comprising a shell, axial ribs carried by said shell and extending inwardly therefrom, and a plurality of chains within said kiln, each of said chains being located between adjacent axial ribs and having its ends attached to said adjacent ribs at axially spaced points at the radially outer portions of said ribs, the length of each chain being substantially greater than the distance along the inside surface of the kiln between the points of attachment of said chain.

4. A rotary kiln comprising a shell, a refractory lining within said kiln, ribs carried by said shell adjacent the inner surface of said lining and extending inwardly therefrom, and a plurality of chains connected at their ends to adjacent ribs at axially spaced points thereon adjacent said lining, the connection points of said chains being so spaced as to provide considerable slack in said chains to sweep over the inner surface of said lining during rotation of said kiln, said chains being so spaced from each other that the areas of lining surface swept by adjacent chains overlap, whereby substantially the entire lining surface of the kiln zone equipped with said chains is kept clean of sticky material.
